DESIGN FOR A COMBINED ADVERTISING SIGN AND CLOCK

Solomon H. Shapiro, New York, N. Y.

Application August 11, 1939, Serial No. 86,610

Term of patent 3½ years

To all whom it may concern:

Be it known that I, Solomon H. Shapiro, a citizen of the United States of America, residing in New York city, in the Borough of Manhattan, county and State of New York, have invented a new, original, and ornamental Design for a Combined Advertising Sign and Clock, of which the following is a specification, reference being had to the accompanying drawing, forming part thereof, wherein the figure is a front perspective

view of a combined advertising sign and clock showing my new design.

The rear of the combined advertising sign and clock is substantially the same in appearance as the front.

I claim:

The ornamental design for a combined advertising sign and clock, substantially as shown, and described.

SOLOMON H. SHAPIRO.
